(57) **CLAIM**

The ornamental design for a faucet remote control as shown
and described.

DESCRIPTION

FIG. 1 is a perspective view of a first embodiment of a faucet
remote control, showing our new design with environmental
subject matter;

FIG. 2 is a perspective view of the faucet remote control of
FIG. 1;

FIG. 3 is a top view thereof;

FIG. 4 is a bottom view thereof;

FIG. 5 is a front view thereof;

FIG. 6 is a rear side view thereof;

FIG. 7 is a left side view thereof;

FIG. 8 is a right side view thereof;

FIG. 9 is a perspective view of a second embodiment of a
faucet remote control, showing our new design;

FIG. 10 is a top view thereof;

FIG. 11 is a bottom view thereof;

FIG. 12 is a front view thereof;

FIG. 13 is a rear side view thereof;

FIG. 14 is a left side view thereof;

FIG. 15 is a right side view thereof;

FIG. 16 is a perspective view of a third embodiment of a
faucet remote control, showing our new design;

FIG. 17 is a top view thereof;

FIG. 18 is a bottom view thereof;

FIG. 19 is a front view thereof;

FIG. 20 is a rear side view thereof;

FIG. 21 is a left side view thereof;

FIG. 22 is a right side view thereof;

FIG. 23 is a perspective view of a fourth embodiment of a
faucet remote control, showing our new design;

(Continued)

FIG. 24 is a top view thereof;
 FIG. 25 is a bottom view thereof;
 FIG. 26 is a front view thereof;
 FIG. 27 is a rear side view thereof;
 FIG. 28 is a left side view thereof;
 FIG. 29 is a right side view thereof;
 FIG. 30 is a perspective view of a fifth embodiment of a faucet remote control, showing our new design;
 FIG. 31 is a top view thereof;
 FIG. 32 is a bottom view thereof;
 FIG. 33 is a front view thereof;
 FIG. 34 is a rear side view thereof;
 FIG. 35 is a left side view thereof; and,
 FIG. 36 is a right side view thereof.
 The broken line shown in the drawings are for the purpose of illustrating environment and portions of the faucet remote control that form no part of the claim.
